UNITED STATES PATENT OFFICE.

FRANK A. GAUGER, OF MILWAUKEE, WISCONSIN, ASSIGNOR OF ONE-FOURTH TO A. J. RADDATZ, ONE-FOURTH TO WILLIAM A. BARTELT, AND ONE-FOURTH TO E. R. JESKE, ALL OF MILWAUKEE, WISCONSIN.

HOT-WATER HEATER.

1,333,614.

Specification of Letters Patent. Patented Mar. 16, 1920.

Application filed December 31, 1918. Serial No. 269,036.

To all whom it may concern:

Be it known that I, FRANK A. GAUGER, a citizen of the United States, and resident of Milwaukee, in the county of Milwaukee and State of Wisconsin, have invented certain new and useful Improvements in Hot-Water Heaters; and I do hereby declare that the following is a full, clear, and exact description thereof.

10 This invention refers to hot water heaters more particularly to that type adapted to be used in connection with hot water boilers.

Another object is to construct a heater for the purpose mentioned which is adapted to 15 encircle a hot water boiler and is provided with means for retarding the gases, thus increasing its efficiency.

A still further object is to provide a boiler to be used in connection with a 20 heater of the class described having an auxiliary heating compartment formed therein making it necessary to heat only a small volume of water.

The invention in one practical form in 25 which it may be embodied is illustrated in the accompanying drawings, in which:

Figure 1 is a sectional view through the invention.

Fig. 2 is a sectional view through the 30 heater attachment removed from the boiler.

Fig. 3 is a sectional view through the burner as indicated by line 3-3 of Fig. 2, and

Fig. 4 is a sectional view taken on line 4-4 of Fig. 2.

35 In the drawings I have shown my heater attached to a range or household boiler 2 embodying special features of construction which make it especially adapted to a heater of the type herein disclosed in which 1 is a cylindrical shell preferably constructed in two sections, in order that it might accommodate boilers of slightly different diameters. At the edges of the two sections of the shell are provided lugs 3 which are secured 40 together by suitable bolts or rivets 4. The upper end of the shell thus formed is restricted to engage the boiler and provided with a flue outlet 5.

50 Adjacent the lower end of the shell are gas passages 6 having necessary ports 7 to form a burner. As clearly shown in Fig. 3 the gas passages 6 are formed in both sections of the shell 1 and are separated by partitions at the abutting edges of the shell.

The intake end of the gas passages are 55 slightly enlarged to form the mixing chambers 6' which are supplied with gas by the valve 11 having two jets 12 communicating with each of the mixing chambers 6'. From this construction it will be seen that should the shells become slightly spaced apart the gas passages will in no way be affected, as would be the case were they connected.

While I have shown the burner cast integrally with the shell it will be readily appreciated that it might be constructed separately and secured thereto in any suitable manner without departing from the invention. The burner 7 is also provided with lugs 8 spaced apart which engage the boiler 70 and at the same time form air inlet passages between the boiler and burner to supply the necessary air for combustion. To further aid combustion I have shown, positioned slightly above the burner, air inlet openings 75 9. Between the top and lower end, at suitable intervals, the shell 1 is provided with baffle plates 10 in staggered relation to each other for the purpose of retarding the heated gases, thereby utilizing the full 80 amount of heat contained therein and increasing the efficiency of the heater.

The boiler 2 is provided with an inner wall 13 forming an auxiliary heating chamber 14 which communicates with the upper 85 end of the main chamber 15 by means of a pipe 16, having branches 16' tapped into the wall 13, at its lower end. Connecting the upper and lower end of the compartment 15 is conventional pipe coil 17 which is 90 associated with a furnace or other suitable heating means. The main chamber 15 is further provided with a supply pipe 18 while an outlet pipe 19 communicates with the auxiliary chamber 14.

In operation it will be seen that when it is desired to use the heater attachment for supplying hot water the pipe 16 will supply the warm water from the top of the main chamber to the auxiliary chamber 14 100 where it will be heated by the hot gases passing up through the shell 1 and coming into contact with the outer wall of the boiler 2. The water is then drawn off from the auxiliary chamber through the outlet pipe 19. 105

While I have shown a heater attachment in connection with a boiler of special construction, it will be understood that I can

attach the same to the conventional form of boiler without departing from the invention and further instead of incasing the entire length of the boiler with the shell 1 I might 5 decrease the length of the same and cover any portion of the boiler with varying results.

What is claimed is:—

1. A heater comprising a pair of like sections adapted to have their corresponding longitudinal edges substantially engaged, each consisting of a substantially semi-cylindrical casting having radially extending 10 staggered baffle plates formed on its inner surface, connecting lugs extending from the casting adjacent its longitudinal edges, and a semi-circular burner tube formed at one end of the casting, one end adjacent one longitudinal edge being closed, the other end 15 adjacent the other longitudinal edge being open and enlarged to form a mixing chamber.
2. The combination with a normally vertically positioned elongated household or 20 range boiler, of a heater therefor comprising a shell substantially the length of the boiler and separable longitudinally into two like parts, said parts being adapted to encircle the boiler, an independent burner 25 head carried by the lower end of each part, lugs extending laterally from the shell parts adjacent their corresponding edge, and fastening elements connecting the adjacent lugs to secure the parts of the shell about the 30 boiler.
3. The combination with a normally vertically positioned cylindrical household or 35 range boiler, of a heater therefor comprising a cylindrical shell of greater diameter than the boiler and substantially the length 40 thereof, said shell consisting of two semi-cylindrical sections adapted to encircle the boiler, spacing means carried by each section to space the same from the boiler, lugs 45 extending laterally from the sections adjacent their longitudinal edges, fastening elements connecting to the adjacent lugs to se-

cure said sections together, a semi-circular burner head carried by the lower end of each section, said heads being independent, 50 and a fuel supply means for said burner heads.

4. In an apparatus of the class described, a boiler casing, a wall spaced inwardly of the casing side wall and having its ends 55 connected with the casing end walls to provide an auxiliary chamber within the casing, an inlet into the main portion of the casing, an outlet from the auxiliary chamber, an inlet from one end of the main portion 60 of the casing to the other end of the auxiliary chamber, a means for heating the contents of the auxiliary chamber.

5. In an apparatus of the class described, a boiler casing, a wall spaced inwardly of 65 the casing side wall and having its ends connected with the casing end walls to provide an auxiliary chamber within the casing, an inlet into the main portion of the casing, an outlet from the auxiliary chamber, an inlet from one end of the main portion 70 of the casing to the other end of the auxiliary chamber, and heating means enveloping the casing to heat the contents of the auxiliary chamber.

75 6. In an apparatus of the class described, a normally vertically positioned cylindrical boiler, an annular wall spaced inwardly of the boiler wall and having its ends connected with the ends of the boiler to provide 80 an outer auxiliary chamber and a main chamber, an inlet into the main chamber, an outlet from the auxiliary chamber, an inlet from one end of the main chamber to the remote end of the auxiliary chamber, a substantially cylindrical heater shell surrounding the boiler and extending substantially throughout the length thereof, and a burner head carried by the lower end of the shell.

In testimony that I claim the foregoing 90 I have hereunto set my hand at Milwaukee, in the county of Milwaukee, and State of Wisconsin.

FRANK A. GAUGER.
